CLAIM

The ornamental design for a base cap for a racquet handle, as shown and described.

DESCRIPTION

FIG. 1 is a perspective view of a base cap for a racquet handle showing our new design;

FIG. 2 is another perspective view with a fragmented handle wrap shown in broken lines for illustrative purposes only;

FIG. 3 is a top plan view of FIG. 1;

FIG. 4 is a side elevational view from the right of FIG. 1;

FIG. 5 is an opposite side elevational view thereof; and,

FIG. 6 is a bottom plan view thereof.
